UNITED STATES PATENT OFFICE.

VERNA O'NEAL WATKINS, OF ATLANTA, GEORGIA.

EDUCATIONAL BOARD.

1,392,726.

Specification of Letters Patent.

Patented Oct. 4, 1921.

Application filed December 27, 1918. Serial No. 268,445.

To all whom it may concern:

Be it known that I, Verna O'Neal Watkins, a citizen of the United States, residing at Atlanta, in the county of Fulton and 5 State of Georgia, have invented certain new and useful Improvements in Educational Boards; and I do hereby declare the following to be a full, clear, and exact description of the invention, such as will enable others 10 skilled in the art to which it appertains to make and use the same.

This invention relates to educational boards, the primary object of the invention is to provide a board structure including a 15 table top having a recess formed therein, and a hinged cover for said recess, which cover is provided with a plurality of openings for receiving pegs of different colors, by means of which pegs and openings, 20 children may form various articles, such as the letters of the alphabet, representations of various common articles, pictures or the like, and further to provide drawers which extend slidably into the ends of the 25 table top for receiving the pegs when not in use.

A further object of this invention is to provide means for supporting the table top or board structure which consists of a plurality of supporting legs having reduced 30 upper ends, which seat in sockets in the corners of the table top or board.

With the foregoing and other objects in view, this invention consists in such novel 35 features of construction, combination and arrangement of parts, as will be hereinafter more fully described, illustrated in the accompanying drawing, and claimed.

In describing the invention in detail, reference will be had to the accompanying 40 drawing, wherein like characters designate like and corresponding parts throughout the several views, and in which:

Figure 1 is a perspective view of the improved educational board, showing the same supported by legs in a horizontal position,

Fig. 2 is a section on the line 2—2 of Fig. 1,

Fig. 3 is a cross section through the center of the board, showing the cover or case positioned on the same,

Fig. 4 is a detail perspective view of the

copy supporting bracket, showing the same positioned on the table, and

Fig. 5 is a side elevation of one of the pins 55 or pegs used in connection with the board.

Referring more particularly to the drawing, 1 designates the table top or educational board as an entirety, which is constructed of any suitable material and is provided 60 with a relatively large recess 2 formed therein intermediate of its ends. The recess 2 is normally closed by a hinged cover or plate 3, which is hingedly connected at 4 to a hinge strap or structure 5, carried by the 65 sides or ends 6 of the board structure. The hinged cover 3 has a clasp or latch 7 carried by its free edge, which co-acts with a section of the latch structure 8 carried by the edge 9 of the board 1.

The hinged cover 3 is provided with a plurality of openings 10, extending therethrough which may be arranged in any desired manner, and these openings are provided for receiving pegs 11, as indicated in 75 Fig. 5 of the drawing, to form representations of various articles or the letters of an alphabet, so that by placing the pegs in various openings in the cover 5, a child may become accustomed to the various articles and thus its education will be greatly advanced.

The pegs 11 may be of various colors, so as to add to the attractiveness or appearance of the representation of the article formed on the board, and it is desired to furnish a book 80 with the game board which will have various illustrations therein, which the child may copy on the board by the use of the pegs 11.

The ends 12 of the board 1 are provided with recesses 14, which extend inwardly 85 from the outer edges, and receive drawers 15, which are adapted to retain the pegs 11 when the pegs are not in use.

The corners of the board are provided with recesses 16, which extend upwardly 90 from the bottom thereof and receive the reduced upper ends 17 of legs 18 which support the board 1 in a horizontal position, as illustrated in Fig. 1 of the drawing. Suitable plates 19 are positioned at the lower 95 ends of the legs 18, and they are provided with recesses 20 for receiving the lower ends of the legs to hold the legs firmly in place.

The book or other work to be copied is

- supported by an easel 21, as shown in Fig. 4 of the drawing. The easel comprises a U-shaped frame having a pair of legs 22, a bight portion 24 and a central brace 23. The brace 23 is connected to the bight portion and extends downwardly and rearwardly therefrom and then bent angularly thereto to provide a horizontal portion 25, which is bent inwardly and arranged to engage the rear edge of the table. The table is provided with a plurality of spaced sockets 26, which are secured by any suitable means to the board, and these sockets are arranged to receive terminals of the legs 22 and brace 25 to hold the easel in position. An angular bracket 27 is secured to the legs 22 and positioned near the bottom thereof and forms means for supporting the book or the copy work to be copied.
- 20 A handle 30 is attached to one edge of the board 1 for use in carrying the board from one place to another, and when it is desired to either store the educational board structure, or carry it, the legs 18, plates 19 and 25 easel structure 21 are placed within the recess 22 and the pegs 11 are placed within the drawers 15, thereby providing a compact article which can be conveniently transported.
- 30 A canvas cover or other fabric receptacle 31, can be provided for completely incasing

the board, when the same is in its flat form, so that the same can be readily transported and the cover can be provided with a suitable handle 32 so that the board can be 35 readily transported.

In reducing the invention to practice, certain minor features of construction, combination and arrangement of parts may necessitate alterations to which the patentee 40 is entitled, provided such alterations are comprehended within the scope of what is claimed.

What is claimed is:

An educational device for simulating a 45 drawing table in kindergarten work comprising a box adapted at its corners to receive legs and provided with a hinged cover, legs adapted to fit within the box and to be inserted at the corners to form a table, the 50 cover perforated throughout a major portion of its area with relatively small juxtaposed holes, pegs adapted to fit the holes whereby characters may be formed upon the table top by inserting the pegs in the 55 perforations.

In testimony whereof I affix my signature in presence of a witness.

VERNA O'NEAL WATKINS.
